JEAN DELATTRE SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF CRACKING HYDROCARBON OILS

Application filed December 24, 1927. Serial No. 242,434.

This invention relates to improvements in process of cracking hydrocarbon oils, and its novel features are more particularly directed to certain improvements in so called vapor phase cracking.

With the increasing advent of combustion engines having high compression ratios, it has been found desirable to use motor fuels containing what are commonly known as anti-knock compounds. These anti-knock compounds are in some instances increased or produced by the formation of a relatively large percent of unsaturates in the gasoline or motor fuel. The present invention is adapted in its novel features to produce these anti-knock compounds in part, at least, through the cracking of the vapors in what is generally known as vapor phase cracking.

The invention is also adapted as part of a continuous process to produce gasoline or gasoline like bodies, which are relatively low in unsaturates. In addition, the process can be so operated as to more or less quantitatively control the percent of unsaturates.

In this application, as will hereafter more clearly appear, I have described my basic process, together with various specific examples which may be carried out utilizing the broader idea of the invention, but with modified details depending upon the results desired, or the character of oil under treatment.

This process is of such a character that the raw charging stock, whether gas oil, fuel oil, crude or reduced crude, or the like, may be first subjected to the well known so called liquid-vapor phase cracking under pressure and certain of the gasoline constituents so formed may then, if desired, be removed from the system, while the reflux condensate from such pressure cracking may then be subjected to vapor phase cracking, or atmospheric or reduced pressures.

By such operation the reflux condensate so formed is preferably separated from the carbon containing residues, and becomes a relatively clean charging stock for the vapor phase cracking operation.

At the same time, if desired, the residue produced from the liquid-vapor phase pres-

sure operation may be flashed and the flashed vapors from the residue also become a highly desirable and relatively clean charging stock for the vapor phase operations. The process may be so carried out that the reflux from the main pressure cracking operation may be independently treated from the vapors produced by the flashing of the residuum, or they may be treated together, as a common vapor phase cracking stock.

Another feature of this invention is that the hydrocarbons which are subjected to the vapor phase cracking, have prior thereto already been so treated by the pressure process as to more or less crack them, whereby the subsequent cracking of such reflux or vapors in the vapor phase part of the process, is much easier than would be the case were the raw charging stock initially subjected to straight vapor phase cracking.

It is well known in present vapor phase cracking that the fuel consumption is high and the incondensable gas loss is large. In addition, in present types of vapor phase cracking the carbon production is high. By means of the present invention the fuel consumption is materially lowered, the gas losses materially reduced, due in part to the ability to crack in the vapor phase at a lower temperature than has heretofore been done, and also the carbon production is materially lessened because of the previously prepared charging stock for the vapor phase operations. These advantages are all obtained without in any way lessening the production of the desirable anti-knock compounds, but quite the contrary such anti-knock compounds are produced in excess of that heretofore possible and with much more satisfactory cracking conditions.

It is to be understood that by means of the present process the oil is so preliminarily treated prior to the vapor phase operation that it is in prime condition for vapor phase cracking, because it has already been initially cracked with the formation of some unsaturates and the vapor phase part of the operation in reality completes the maximum formation of anti-knock compounds already previously started.

Heretofore vapor phase processes have only been partially successful on gas oil, but by the present invention heavy fuel oils or crude petroleum may be cracked to obtain the maximum amount of gasoline, and certain of the constituents thereof converted into a maximum amount of anti-knock compounds.

Another feature of the invention is that the reflux produced from the vapor phase cracking, may, if desired, be mixed with the raw charging stock in the pressure part of the process, and inasmuch as this reflux contains in itself a large amount of anti-knock compounds the gasoline from the pressure part of the process will in such case be produced with a large amount of anti-knock compounds.

I have above referred to a certain part of the process as liquid-vapor pressure operation and another part as vapor phase cracking at atmospheric pressure. It is to be understood, however, that in its broader aspect the invention is not limited to the vapor phase cracking at atmospheric pressure, as good results may be obtained even though the vapor phase cracking part of the operation is carried out at superatmospheric pressure or at subatmospheric pressure. For example, the liquid-vapor pressure part of the process may be at say 100 lbs. upwards and the vapor phase cracking at pressures of 50 lbs. or lower.

It is to be understood that these figures are merely illustrative and in no sense intended to limit the scope of invention on the degree of pressure.

The invention will be more clearly understood from the following description, reference being had to the accompanying drawing.

This drawing shows a diagrammatic illustration of an apparatus and in my opinion a novel form of apparatus suitable for carrying out the invention. It is to be understood that this diagrammatic drawing is not to scale or intended to be.

Referring to the drawing, a cracking coil 1 is positioned in a suitable furnace 2. Raw oil is supplied to the coil 1 through feed line 3 and feed pump 4, leading to any suitable source of supply. The oil passes from coil 1 to transfer line 5, having throttle valve 6, into expansion chamber 7. The vapors pass out of expansion chamber 7 through vapor line 8 and thence, if desired, into the lower side of dephlegmator 9. Throttle valve 10 is interposed in line 8 for a purpose herein-after described.

From the top of the dephlegmator the vapors may pass through vapor outlet pipe 12, into condenser coil 14, and then to receiver 15. Receiver 15 is provided with gas outlet control valve 16, and liquid draw off control valve 17.

The temperature of the dephlegmator may

be controlled either by introducing raw oil directly into the vapors in the dephlegmator through pipe 18, having control valve 19, or in the event it is undesirable to introduce the raw oil directly to the dephlegmator, as is true in certain cases hereinafter described, then the raw oil may be fed through a closed coil 20, which closed coil may, if desired, lead the oil in its passage thereto, to the pump 4.

The reflux condensate from the dephlegmator 9 is drawn off through the lower end thereof through pipe 21, and thence may be returned through lines 21 and 22 and pump 23 to the raw oil feed line 3. A by-pass 24 may be provided in line 22 around the pump 23, suitable valves 25 being provided as shown.

In the line 21, is provided a throttle valve 26. The reflux may also be passed through line 27 and branch 28 to vapor phase feed line 29, hereinafter referred to.

A pump 30 may be interposed in line 27, and a by-pass line 31 around the pump may also be provided, throttle valves 32 being interposed as shown in the drawing.

The reflux condensate may instead of being sent through branch 28, after it reaches 27, be diverted through pipe 33, having throttle valve 34, and then combined with the residuum drawn off from chamber 7 by means of draw-off line 35 and branch 36, the latter leading to the residuum flash chamber 37. A valve 38 is interposed in the line 36 and a throttle valve 39 is interposed in an extension of the line 35, below the juncture of the line 35 with the line 36, whereby some of the residuum may be drawn entirely out of the system, if desired.

The vapors which are flashed from the flash chamber 37 pass out through the upper part thereof through pipe 40, having throttle valve 41 and thence to the line 29. At the lower end of the flash chamber 37 is a residuum draw off 42 having throttle control valve 43.

In certain cases the flash chamber 37 may be by-passed and the chamber 7 used as a combined reaction or expansion and flash chamber. In such cases all of the vapors from chamber 7 may either pass to the dephlegmator 9, or they may pass directly to line 29 by means of a branch pipe 44, having throttle valve 45.

A throttle valve 46 may be interposed in line 8 as well as valve 47—A in line 29, for a purpose hereinafter described. This line 29 leads to the vapor phase cracking coil 47, seated in a suitable furnace 48. The outlet end of the coil connects through delivery line 49 having throttle valve 50, into chamber 51. This separating chamber 51 is provided with a carbon or residue draw off pipe 52, having throttle valve 53, and with vapor outlet pipe 54, having throttle valve 55. The pipe 54 leads to the side of dephlegmator 56. The temperature in this dephlegmator may be con-

trolled either by introducing raw oil directly into dephlegmator 56, by pipe 57, having control valves 58, or if desired raw oil may be passed through the closed coil 59, and thence if desired led to the feed pump 4. The raw oil is not introduced directly into either dephlegmator unless it is desired to send it to the pressure cracking coil 1, or unless it is of such a character that it is so clean a charging stock that it can be passed directly to the vapor phase cracking coil 47, without materially increasing carbon formation in the vapor phase coil.

The vapors pass out of dephlegmator 56 through vapor line 60 to condenser coil 61 and thence to receiver 62, which is provided with gas outlet control valve 63 and liquid outlet control valve 64. If desired the vapors from dephlegmator 9 may also pass into receiver 62, thus eliminating receiver 15. To this end a vapor pipe 65 having control valve 66 may lead from the line 12 to the line 60.

The reflux condensate from dephlegmator 56 passes out of the lower end through pipe 67, and thence through pump 68 to line 69. The by-pass 70 may be provided around the pump with the usual valves 71. The reflux from line 69 may be passed directly, if desired, to line 29, by means of pipe 72, having throttle valve 73 and line 28, or if desired it may pass via line 72 into line 33 by opening the valve 34 and closing the valve 74 in the line 28, or the condensate may be passed from the pipe 69 into the line 22 by closing the valve 73 and opening the valve 75. The reflux from either dephlegmator may be drawn out of the system through branch 77 having throttle valve 78, or branch 79, having throttle valve 80.

40 Describing now the manner in which the invention may be operated, one desirable method of carrying out the invention is to subject the raw charging stock to a liquid-vapor phase pressure cracking operation, flash the residuum therefrom and subject the flashed vapors to vapor phase cracking at atmospheric pressure or pressure lower than the main pressure, and to also subject the reflux condensate from the main dephlegmator to vapor phase cracking. In such case, the raw oil, if desired, may be passed through the dephlegmator connecting the vapor phase cracking coil, either in direct or indirect contact with the vapors in such dephlegmator and thence to the main cracking coil. The reflux from the second dephlegmator or the dephlegmator connected to the vapor phase cracking coil, is or may be returned to the main high pressure cracking coil.

60 Describing the above method of carrying out the invention more in detail, the raw oil is fed into the coil 1 where it may be heated to a transfer temperature of say 750° F. to 900° F. more or less and thence into the expansion chamber 7. The vapors pass out of

expansion chamber 7 through line 8 into main dephlegmator 9. Here the heavier portions are condensed while the lighter vapors pass out through line 12, either into receiver 15 or receiver 62 by suitably regulating the valves shown in the accompanying drawing. The reflux condensate may be drawn out through pipe 21 and thence if desired pass through pipes 31, 27 and 28 into the line 29, and thence to the vapor phase cracking coil 47. If desired, the reflux condensate instead of passing to pipe 28 may go from pipe 27 via the pipe 33, to the line 36. The residuum is drawn off the bottom of chamber 7 continuously and thence may be passed through the pressure reducing valve 38, and be flashed into chamber 37. The vapors from such flashing operation thence pass through the pipe 29 into the vapor phase coil 47. A pressure of 100 lbs. upwards may be maintained in coil 1, chamber 7, dephlegmator 9 and on receiver 15, by suitably regulating the valves 16 and 17 on receiver 15 and valves 32 and the reducing valve 38. If desired the valves 74 and 34 may be used as reducing valves depending upon whether the line 28 or 33 is used instead of using valves 32.

The vapors from the flashing chamber 37 mix with the reflux condensate from the dephlegmator 9 as they pass through the vapor cracking coil 47, and are there subjected to temperatures in said coil of say 900° to 1150° more or less.

It is to be understood that the temperatures here given are illustrative as well as the temperatures in the transfer line 5. The vapor phase cracking coil may be maintained under substantially atmospheric pressure, or if desired, under a pressure somewhat above atmospheric, say 20 to 50 lbs. more or less. If desired, the vapor phase cracking coil may be even maintained under a vacuum, by connecting suitable vacuum pump not shown to the receiver 62. In such case the pump 68 may be used as a double action pump, vacuum on the inlet and pressure on the discharge side. The contents of vapor phase coil 47 are then preferably passed to chamber 51 where any carbon containing portions may be dropped out and be drawn out of the system, while the balance goes through the line 54 to dephlegmator 56. In this dephlegmator 56 the heavier portion will be condensed, and may then be passed through the lines 67 and 69 directly back to the main heating coil 1. In such case the valves 26 and 73 are closed and the reflux condensate from dephlegmator 56 may then readily pass directly to coil 1. The portion of the oil which is passed through the vapor phase cracking coil is converted into a relatively large percent of unsaturated aromatics or other anti-knock compounds, and may then, if desired, be blended with straight run gasoline or with gasoline produced by the pressure operation. The raw

charging stock used may, as heretofore stated, be either gas oil, heavy fuel oil or crude, and it may be noted that by the present invention I not only crack such heavier oils but in doing so separate out therefrom highly desirable clean charging stock already partially cracked, which is very suitable for the vapor phase operation.

At the same time it will be noted that the charging stock which goes to the vapor phase cracking coil has not only been partially cracked as heretofore stated, but it thus necessitates a minimum amount of additional fuel for the vapor cracking coil. Furthermore, inasmuch as the portion of the oil which passes through the vapor phase cracking coil has already been more or less cracked lower temperatures may be used in the vapor phase coil, thus materially lessening the objectionable high gas losses incident to heretofore known vapor phase cracking processes. It will be further noted that by this process the gasoline produced by the pressure operation of the process is removed and not subjected to the vapor phase cracking. In addition, if the reflux condensate from the vapor phase cracking operation is returned to the main cracking coil then the gasoline formed by the pressure part of the process will have mixed with it a certain amount of desirable anti-knock compounds.

Another important feature of this manner of carrying out the invention is that the rate and extent of cracking in the pressure part of the process may be regulated entirely independently of the vapor phase part of the cracking, and also the reverse is true.

While I have stated that by this process the vapor phase cracking can be carried out at a lower temperature than in certain heretofore known processes, it is to be understood that I in no sense limit myself to such temperatures relative to prior processes, because it may be desirable to subject the oil passing through the vapor phase cracking coil to very high temperatures, and while this, of course, will not tend to lessen the gas losses, nevertheless the process will still have the advantages of a low fuel consumption and a highly desirable charging stock.

Certain features disclosed but not specifically claimed herein comprise the claimed subject matter of my copending applications Serial Nos. 242,435, 242,436, and 242,438, filed on even date herewith.

I claim as my invention

1. A process for cracking hydrocarbon oil, which comprises passing the oil through a heating coil and thence into an expansion chamber under pressure, taking off vapors from said expansion chamber and subjecting them to reflux condensation to form reflux condensate, withdrawing the residuum from said chamber and flash distilling it at reduced pressure, then subjecting the vapors from

said flash distillation and said reflux condensate to vapor phase cracking, removing the vapors from said vapor phase cracking step, subjecting them to reflux condensing action and returning said reflux to the main heating coil for further cracking. 70

2. In a hydrocarbon oil cracking process, the improvement which comprises subjecting the oil to cracking conditions of temperature and pressure in an initial cracking zone, separating the evolved vapors from the unvaporized oil, removing said unvaporized oil and reducing the pressure thereon, thereby forming additional vapors, and subjecting said additional vapors to vapor phase cracking in a vapor phase cracking zone, dephlegmating the vapor phase cracked vapors thereby forming reflux condensate, and returning one portion of said reflux condensate to said initial cracking zone and another portion thereof to said vapor phase cracking zone. 75 80 85

3. In a hydrocarbon oil cracking process, the improvement which comprises subjecting the oil to cracking conditions of temperature and pressure in an initial cracking zone, separating the evolved vapors from the unvaporized oil, removing said unvaporized oil and reducing the pressure thereon, thereby forming additional vapors, and subjecting said additional vapors to vapor phase cracking in a vapor phase cracking zone, dephlegmating the vapor phase cracked vapors thereby forming reflux condensate, and returning reflux condensate to said initial cracking zone. 90 95 100

4. In a hydrocarbon oil cracking process, the improvement which comprises subjecting the oil to cracking conditions of temperature and pressure in an initial cracking zone, separately removing the evolved vapors and unvaporized oil, dephlegmating the evolved vapors under pressure, thereby forming reflux condensate, reducing the pressure on said reflux condensate to effect vaporization thereof, reducing the pressure on said unvaporized oil to form additional vapors, and subjecting said additional vapors and the vapors formed by reduction of pressure on the reflux condensate to vapor phase cracking, dephlegmating the vapor phase cracked vapors, thereby forming additional reflux condensate, and returning one portion of said additional reflux condensate to said initial cracking zone and another portion thereof to the vapor phase cracking. 110 115 120

5. In a hydrocarbon oil cracking process, the improvement which comprises subjecting the oil to cracking conditions of temperature and pressure in an initial cracking zone, separately removing the evolved vapors and unvaporized oil, dephlegmating the evolved vapors under pressure, thereby forming reflux condensate, reducing the pressure on said reflux condensate to effect vaporization thereof, reducing the pressure on said unvaporized 125 130

- oil to form additional vapors, and subjecting said additional vapors and the vapors formed by reduction of pressure on the reflux condensate to vapor phase cracking, dephlegmating the vapor phase cracked vapors to condense insufficiently cracked fractions, and returning at least a portion of the condensed insufficiently cracked fractions, to said initial cracking zone.
- 10 6. In a hydrocarbon oil cracking process, the improvement which comprises subjecting the oil to cracking conditions of temperature and pressure in an initial cracking zone, separately removing the evolved vapors and unvaporized oil, dephlegmating the evolved vapors under pressure, thereby forming reflux condensate, reducing the pressure on said reflux condensate to effect vaporization thereof, reducing the pressure on said unvaporized oil to form additional vapors, and subjecting said additional vapors and the vapors formed by reduction of pressure on the reflux condensate to vapor phase cracking, dephlegmating the vapor phase cracked vapors to condense insufficiently cracked fractions, and returning at least a portion of the condensed insufficiently cracked fractions to the vapor phase cracking.
